UNITED STATES PATENT OFFICE

2,106,184

GAS GENERATOR

Vincent D. McDonnell, Chicago, Ill.

Application May 21, 1934, Serial No. 726,691

7 Claims. (Cl. 48—61)

This invention relates to gas generators and particularly to a method, and portable apparatus, for producing a gaseous fuel from liquid crude or fuel oil.

5 The main objects of this invention are to provide an improved method of producing methane or other combustible gas; to provide an improved gas generator that will convert liquid fuels into a fixed gas adapted to operate internal combustion engines or any gas consuming device; to provide in such a device a simple portable unitary structure adapted to be associated directly with the engine of a motor driven vehicle; to provide such a device in which the heat energy 10 of primary combustion is utilized to support endothermic reactions within the device and produce a fixed gas; to provide such a device arranged to automatically control the rate of gas production according to the demand of an associated gas consuming device; to provide such 15 a device having an improved igniting means; to provide such a device having improved means for introducing automatically regulated quantities of water for vaporization and dissociation; and to provide in such a device an improved catalyzer for affecting the gaseous product.

A specific embodiment of this invention is shown in the accompanying drawings in which:

Figure 1 is a view showing an end elevation of 30 an improved gas generator.

Fig. 2 is a view showing a front elevation of the same.

Fig. 3 is a view showing a partially sectioned front elevation of the same.

35 Fig. 4 is a sectional view of the same taken on the line 4—4 of Fig. 3.

Fig. 5 is a sectional view of the same taken on the line 5—5 of Fig. 3.

40 Fig. 6 is a fragmentary sectional view of the same taken generally on the line 6—6 of Fig. 5 and partially on line 6—6 of Fig. 4.

Fig. 7 is a sectional view taken on line 7—7 of Fig. 6, and showing the primary driving gears of the device.

45 Fig. 8 is a sectional view taken on line 8—8 of Fig. 6 and showing a circuit breaker.

Fig. 9 is a sectional view taken on line 9—9 of Fig. 6 and showing the igniting fluid supply device with the overflow plunger in depressed position to supply igniting fluid.

50 Fig. 10 is a sectional view taken on line 10—10 of Fig. 6 and showing a fuel oil level control device.

55 Fig. 11 is a sectional view taken on line 11—11

of Fig. 3 and showing details of a water supply connection.

Fig. 12 is an enlarged sectional view showing details of a coupling and valve arrangement.

Fig. 13 is a fragmentary sectional view showing 5 a shutter arrangement for air and water vapor inlet ports.

Fig. 14 is an enlarged fragmentary view of the igniting fluid supply device showing an arrangement of contacts for primary ignition. 10

In the form shown in the drawings the improved gas generator comprises a housing 1 arranged to provide a combustion chamber or space 2. A catalyzing chamber or space 3 located directly above and opening into the combustion chamber 2, and a fuel bowl 4 formed in the lower portion of the combustion chamber and adapted to hold a quantity of liquid fuel. The fuel bowl 4 is arranged to open directly into the combustion chamber 2 and a horizontally disposed rotatable 15 drum 5 is positioned within the combustion chamber so that a portion of its surface extends into the fuel bowl 4 and below the surface of the liquid fuel held therein. The rotatable drum 5 is carried upon a shaft 6 and is preferably provided with an asbestos wicking 7 wound about its periphery and adapted to carry fuel from the bowl 4 into the combustion chamber 2 where the fuel 20 is burned.

Disposed within the catalyzing chamber 3, 30 which extends upwardly from the combustion chamber 2, is a catalyzer which comprises, in the present form, a plurality of catalyzing plates or discs 8, and the gases produced by combustion in the chamber 2 pass over and between the plates 35 8 and out of the device through the outlet 9 located at the top of the catalyzing chamber.

The housing 1, as shown, is a single casting having one of its sides open, that is the left side in Figs. 2, 3, and 6, and a closure for the open side is provided by the side plate 10 which is bolted to the housing as shown in Fig. 1. Within the housing and defined by the bottom 11 of the fuel bowl 4 and the wall 12 is a cooling jacket 13 which extends the length of the fuel bowl and includes the 40 sides thereof as shown in Fig. 5. A cooling medium such as water is circulated within the jacket 13 and it is the function of this jacket to keep the fuel in the fuel bowl from boiling.

An air chamber or space 14 is formed at the 50 lower front side of the housing and extends the length thereof, being defined by the wall 12 of the cooling jacket and the front and bottom outer walls of the housing 1. The air chamber 14 extends upwardly along the front wall of the hous- 55

ing and communicates with an air passage 15 which extends horizontally across the front of the housing parallel to the axis of the drum 5, and which is provided with a series of ports 16 arranged in a horizontal row and opening into the combustion chamber 2 adjacent the periphery of the drum 5.

The air chamber 14 is normally under suction, as will be hereinafter explained, and air is introduced therein through an intake opening 17 in the bottom of the housing. A valve 18, slidably mounted on a vertical stem 19, serves to close the opening 17 through coaction with a spider-like member 20 spanning the opening 17 and having an annular marginal rim which is engaged by the valve 18. The member 20 is secured to the bottom of the housing and carries the vertical stem 19 upon which the valve 18 is slidably mounted. The valve 18 is provided with a counter bored boss 21 through which the rod 19 passes, and within the counter bore is a helical spring 22 arranged to bear against the end of the counter bore and the hub of the member 20. The spring 22 is designed to almost counter balance the weight of the valve 18 so that only a slight pressure differential between the chamber 14 and the atmosphere will cause the valve 18 to open and admit air into the housing.

The rear wall 23 of the housing casting is set forward of the rear end of the housing side walls and is provided with a plurality of integral transverse baffles 24 which are spaced apart vertically from adjacent the fuel bowl to the top of the housing. These baffles are all inclined downwardly, alternate baffles being downwardly inclined toward one side of the housing and the others toward the opposite side of the housing, and the lower end of each baffle is terminated short of the adjacent housing side wall so as to provide communication between successive spaces between the baffles. The baffles 24 are of a width equal to the amount that the rear wall is set forward of the rear ends of the side walls, and a cover plate 25, which extends over the entire area of the rear wall occupied by the baffles, is provided so that a continuous enclosed zig-zag passage 26, leading from the top of the housing to adjacent the fuel bowl, is formed between the cover plate 25 and the rear wall 23 of the housing.

The zig-zag passage 26 serves the function of a water vaporizer, obtaining its heat from the combustion chamber 2 and the catalyzing chamber 3, and communicates through a passage 27 extending across one side of the housing, with a steam distributing passage 28 which is located directly above, and extends parallel with, the air passage 15. Steam ports 29 connect the steam passage 28 with the combustion chamber 2 adjacent the side of the drum 5, and are spaced apart in a horizontal row along the side of the drum in the same manner as the air ports 16.

The drum 5 is carried on the shaft 6 by means of a pair of hubs 30, one at each end of the drum, which are secured in any suitable manner to the shaft, and the shaft 6 is journaled in the bosses 31 which project inwardly from the shaft carrying plates 32 and 33, the shaft engaging portion of each hub 30 being set back as at 34 to receive the respective boss 31. The shaft 6 extends through the carrying plate 32 and carries a driving gear 35 which is secured on the shaft between the carrying plate 32 and the end cover plate 10.

The shaft carrying plates 32 and 33 are arranged to support the catalyzers as well as the drum 5 and for this purpose extend upwardly from

the combustion chamber and into the catalyzing chamber as shown in Figs. 3 and 6.

The catalyzers, as shown in Figs. 3 and 6, preferably comprise the plates 8 which are flat discs having serrated margins as at 8.1, and these discs are spaced apart in horizontal rows on the rotatable shafts 36 which are disposed parallel to each other within the catalyzing chamber 3. In the form shown the shafts 36 are hexagonal in section and pass through hexagonal central apertures in the discs 8 so that the discs are fixed to the shaft to rotate therewith, the discs being spaced apart by spacer members 37 so as to prevent them from shifting axially on the shaft, and the discs on adjacent shafts are arranged with the discs of one shaft positioned opposite the spaces between the discs of the other shaft.

The shafts 36 are suitably journaled in the bosses 38 which are integral on the carrying plates 32 and 33, and are spaced from each other so that the plates 8 of one shaft marginally overlap the plates of the next adjacent shaft. The diameter of the plates 8 is preferably such that they will substantially span the depth of the catalyzing chamber 3, as shown in Fig. 5, and it is this measurement that determines the spacing of the catalyzer shafts 36 since it is preferable that the extremities of the discs barely clear the spacers on the next adjacent shaft. The discs 8 are made from a suitable catalyzing material which has the property of withstanding the extremely high temperatures that are developed in the gases passing over them when the device is in operation, and it is preferable that the first two rows from the bottom or entering end of the catalyzer be of a material such as carborundum and that the succeeding rows be of nickel steel or Invar steel, the shafts in each case being of nickel or Invar steel.

The catalyzer shafts 36 are arranged to extend through the bosses 38 of the carrying plate 32 and on their outer ends, between the plate 32 and the end wall 10, carry gears 39 by means of which they are rotated. The gears 39 are preferably of equal dimensions and are arranged to mesh with each other for mutual rotation. The lowermost gear 39 also meshes with a pinion 40 carried on the inner end of a shaft 41 which is journaled in the boss 42 on the outside of the end plate 10 and extends into the space between the end plate 10 and the carrying plate 32. The pinion 40 is the inner driving gear for the drum and catalyzers and meshes with the gear 35 so that the shafts 6 and 36 are rotated simultaneously.

As shown in Figs. 3 and 6 the shaft carrying plates 32 and 33 are offset inwardly above the combustion chamber and the bosses in which the catalyzer shafts are journaled are disposed on the outer side of the carrying plates. The plates 32 and 33 are shaped to fit the fore and aft sectional contour of the catalyzing and combustion chambers and in this way serve to confine the gases and heat produced in the device to the space occupied by the catalyzing discs 8. Thus the bearings or journals for the shafts 36 and the gears 35, 39 and 40 are substantially protected from the heat. The journals within the bosses 31 which support the drum shaft 6 are protected by the hubs 30 of the drum.

The drive for my improved gas generator is by way of a gear box 43 which is disposed on the outside of the removable end plate 10 and into which the shaft 41 carrying the main driving pinion 40 extends. The gear box 43 is formed as a part of a secondary cover plate 44 which

extends downwardly from the position of the shaft 41 and lies against the edge of an outwardly extending continuous wall 45 integral on the end plate 10 and projecting outwardly therefrom to provide a chamber within which certain apparatus that will be hereafter described is housed, the secondary cover plate 44 being bolted to bosses formed in the wall 45 as indicated in Figs. 1 and 4.

10 Power is transmitted into gear box 43 by means of a shaft 46 which extends through the gear box in a direction parallel to the front face of the housing 1 as shown in Figs. 2 and 3. The shaft 46 is suitably journaled in the gear box 43 and is driven by any suitable means by way of a flexible shaft or other suitable connection, not shown. This connection may be directly to some positively driven rotating element of a motor that may be driven by the gas produced in the herein-described generator, which motor is also not shown.

20 Within the gear box 43 the shaft 46 carries a small pinion 47 which meshes with a spiral gear 48 carried on a shaft 49 suitably disposed and journaled within the gear housing. The shaft 25 49 also carries a second spiral gear 50 which meshes with a driving gear 51 secured on the shaft 41.

25 The gearing contained in the gear housing 43 is all properly proportioned to give the necessary speed reduction so that the rotating parts within the generator will be driven with a proper speed ratio relative to the speed of the driving motor.

30 The space between the secondary cover plate 35 44 and the end plate 10, and surrounded by the wall 45, is divided into two portions by a partition 52 as shown in Fig. 4. The lowermost portion 53 is shaped to provide an involute centrifugal pump housing within which is disposed a pump impeller 54. The pump impeller 54 is carried by a shaft 55 which extends through the secondary cover plate 44 and on which is mounted a pulley 56, the pulley 56 being driven by means of a belt 57 from a pulley 58 carried on 45 the shaft 46 outside of the gear housing 43.

35 The intake 59 to the pump housing 53 is concentric with the shaft 55 and is connected to the water supply intake 60 by way of a passage formed on the outer surface of the plate 44 by a continuous outwardly projecting wall integral on the plate 44 and a small closure plate 61. The intake 60 is connected by means of a suitable hose or pipe to a cool water supply reservoir, not shown.

40 The discharge from the pump 54 is directed through a passageway leading from the pump housing 53 to an opening 62 through the end plate 10 and into the cooling jacket 13 at its lowermost point.

45 The shaft 55 supporting the pump impeller 54 extends through a gland 63 mounted on the closure plate 61 and its outer end is carried in a bracket arm 64 suitably mounted on the secondary cover plate 44.

50 The cooling water circulated by the pump impeller 54 through the water jacket 13 is discharged through an opening 65, in the end plate 10, communicating with the cooling jacket 13 adjacent its upper most point, as shown in Fig. 4, and this discharge opening 65 is connected by way of suitable hose or piping to the cooling water reservoir which is not shown.

55 The remaining space 66 between the secondary cover plate 44 and the end plate 10 houses a

sludge ejector 67 which comprises a chain riding on two vertically spaced sprockets 68 and 69. The bottom end of the space 66 communicates with the fuel bowl 4 at its lowermost point by way of an aperture 70 through the end plate 10 and the top of the space 66 opens into a discharge chute 71 through which sludge is ejected from the apparatus. The discharge chute 71 is disposed above the level of the oil held in the fuel bowl 4 which prevents any loss of fuel and the sludge is carried from adjacent the aperture 70 to the opening 71 by means of small elevator blades 72 which are carried by the chain 67. The blades 72 are pivotally secured on the chain 67 and held in a proper position by means of suitable springs, not shown, which are arranged to permit backward pivotal movement of the blades 72 and to automatically return them to their normal sludge carrying position as shown in Fig. 4.

20 A small lug or pin 73 is provided at the upper portion of the ejector chamber 66 so as to engage the tips of the blades 72 and cause them to pivot backwardly as they are carried past the lug 73 by the chain. As the blades 72 pass over the lug 25 or pin 73, they are snapped back into their normal position by means of their springs and thus throw any sludge that they might carry outwardly through the opening 71.

25 The uppermost sprocket pinion 69 over which the sludge ejector chain travels is carried on an extension of the shaft 6 and power is thereby supplied for operation of the ejector.

30 The oil supply to the fuel bowl 4 is controlled by a float box 74 mounted on the end of the housing 1 opposite the removable end plate 10 and communicating with the fuel bowl 4 by way of an opening 75 through the end wall of the housing 1.

35 The float box 74 is shown in detail in Figure 40 10 and receives oil from a reservoir, not shown, through a connection 76 which enters at the top of the float box through a valve arrangement 77, shown in detail in Fig. 12, mounted on a float box 45 cover plate 78.

40 The valve arrangement 77 comprises a small port 79 which is opened and closed by a plunger 80 operated by a float arm 81 pivotally attached at one end to the cover plate 78, carrying a float 50 82 at its other end.

45 The opening 75 which leads from the float box 74 into the fuel bowl 4 is of sufficient proportion so that the normal level of the oil in the float box and the fuel bowl will be intermediate its top and bottom ends. Thus a variation of the oil 55 level upward or downward, sufficient to properly operate the float 82 and valve 77, may be had without cutting off the flow of oil between the float box and the fuel bowl. This arrangement permits sudden variations of the quantity of fuel 60 consumed in the combustion chamber and at the same time permits a sufficient drop in level so that the float valve may operate to supply fuel from the reservoir through the connection 76 65 without any danger of the fuel level in the bowl 6 falling beyond a point where the wicking 7 on the drum 5 would be likely to run dry.

65 As shown in Figures 3 and 10, the float box is provided with a gauge glass 83 by means of which 70 the level of the fuel in the float box and the fuel bowl can be readily observed.

70 The ignition means for the herein-described gas generator comprises a spark plug 84 disposed in the housing 1 so as to extend into the combustion 75

chamber 2 and connected to a suitable source of electrical energy, not shown.

The initial starting of the apparatus is preferably accomplished by means of a perforated ignition tube 85 which extends into the combustion chamber and along the upper surface of the drum 5. The spark plug 84 is disposed so that its points are located adjacent the tube 85 or preferably within the tube 85 and the tube 10 is connected from the outside of the housing 1 to a supply of fuel having a low flash point, preferably gasoline, which, when supplied to the ignition tube 85, is ignited by the spark plug and serves to ignite the fuel oil carried by the 15 wicking 7 on the drum 5.

Gasoline or other suitable ignition fluid is supplied to the ignition tube 85 by means of a float box 86 suitably mounted on the same side of the housing 1 as the oil float box 14.

The float box 86 is shown in detail in Fig. 9 and comprises a chamber having a cover 87 which is provided with a float valve mechanism 88 having connection by way of a tube 89 with an ignition fluid reservoir, not shown. The float valve mechanism 88 is substantially the same as the above-described float valve mechanism 17 of the fuel oil float box and will, therefore, not be further described.

The ignition fluid float box 86 is arranged to carry a supply of the ignition fluid at a predetermined level and the connection 90 which conducts the fluid to the ignition tube 85 is arranged to enter the float box 86 at a point just above the normal level of the fluid contained therein. The ignition fluid is supplied to the connection 90 and thence to the ignition tube 85 by raising the level of the fluid and causing it to overflow from the float box 86 into the connection 90. Such overflow is brought about 40 by forcing a plunger 91 having an enlarged head 92 below the normal level of the fluid in the float box.

The plunger 91 is a U-shaped member, one leg of which extends through the cover 87 and carries the enlarged head 92, and the other leg of which extends through a suitable guide 93 on the outside of the float box, this other leg being connected by suitable means, not shown, to an actuating means such as a starter mechanism, 50 also not shown.

The spark plug 84 receives its energy from two sources, one of which continuously provides an intermittent spark while the apparatus is running, and the other of which provides a 55 prolonged spark during the initial ignition period. The prolonged spark may be caused by an arrangement such as shown in Fig. 14 in which one contact 94 is carried on the outer leg of the U-shaped plunger rod 91 and arranged 60 to engage a spring contact 95 suitably mounted on and insulated from the float casing 86. A wire, not shown, leads from one of the contacts to the spark plug and another wire, not shown, leads from the other contact to a source of electrical energy, such as a spark coil.

The intermittent spark is provided by a breaker mechanism mounted on a cover plate 96 which provides a closure for the gear housing 43. This breaker arrangement is shown in detail in Figure 8, and comprises a stationary contact 97 and a shiftable contact 98 which is spring actuated so as to be normally urged into engagement with the fixed contact 97.

The breaker is actuated by the squared end 99 75 of the shaft 41 which extends into the breaker

housing, the squared end 99 being engaged by a lug or follower 100 carried by the shiftable arm of the contact 98. Thus as the shaft 41 is rotated, the shiftable contact 98 is caused to intermittently engage the fixed contact 97 as the lug 100 rides on the cam surface formed by the squared end 99 of the shaft 41 and a circuit through suitable wiring, not shown, to the spark plug 84 is intermittently closed and opened as the apparatus operates.

As shown in Figure 6, the circuit breaker is surrounded by an outwardly projecting wall 101 integral on the cover plate 96, and is enclosed by smaller cover plate 102.

Water is supplied to the passage 26 of the water vaporizer by means of an intermittent feeder 103, mounted on the upper part of the housing 1 and shown in Figs. 1 to 4 inclusive and Fig. 11. The feeder 103 comprises a float chamber having an inlet connection 104 at its top which is connected to a suitable supply reservoir and controlled by a valve, not shown, actuated by a float 105. The feeder 103 comprises two sections; one section holds a supply of water and the other section, indicated by 106, communicates with the passageway 26 in the rear wall of the housing 1 by means of a connection 107. The connection 107 is preferably provided with a glass insert and arranged with sight apertures so that the passage of water therethrough may be observed.

The feeder section 106 is separated from the portion holding the water supply by means of a vertical wall or partition 108 which is arranged to extend above the normal water level and water is carried or lifted over the partition 108 by means of a paddle 109 carried on a pivoted shaft 110. The shaft 110 is provided with a crank arm 111 to which is attached a downwardly extending rod 112 which extends into a housing 113 enclosing a ratchet 114 and a pivoted pawl 115. The housing 113 is integral on the end plate 10 and is closed by a cover plate 116. The ratchet 114 is mounted on an extension of the uppermost catalyzer shaft 36 which projects through the end plate 10 and into the housing 113. Thus as the apparatus is operated and the shaft 36 rotated, the ratchet 114 imparts a reciprocal movement to the pawl 115 which is transmitted to the rod 112, so as to actuate the paddle 109, the rod 112 being normally urged 40 downwardly into contact with the pawl 115 by a spring 116 attached to the crank arm 111.

As shown in Figures 4 and 11, the paddle 109 is adjustable transversely of the shaft 110 so that it may be caused to lift more or less water 55 over the partition 108, the adjustment being secured by means of a set screw 117. Thus at each movement of the paddle, as caused by the ratchet 114 through the push rod 112, a definite amount of water is lifted over the partition 108 60 into the portion 106 from which it passes through the passage 107 into the vaporizing passageway 26.

An arrangement for varying the size of the air and steam openings 16 and 29 into the combustion chamber 2 is shown in detail in Fig. 13 and comprises a pair of slides or shutters 118 and 119 arranged to extend over the respective rows of apertures 16 and 29. Each of the shutters 118 and 119 is provided with apertures 16.1 and 29.1 70 respectively spaced so that they may register with the apertures 16 and 29. The slides 118 and 119 are each carried on headed pins or screws 120 which extend through slots 121 in the slides and one end of each slide is arranged to be in thread-

ed engagement with a respective adjusting screw 122 or 123 which extends through one end of the housing 1. Thus from the outside of the housing 1 the slides may be adjusted so as to vary the size of the air and steam openings 16 and 29 respectively and properly adjust the quantities of these mediums introduced into the combustion chamber.

The herein-described apparatus is also provided with an oil overflow connection communicating with the fuel bowl at a point just above the proper level of the fuel that is to be carried therein. Such an overflow is provided to prevent flooding of the combustion chamber and is indicated by 15 124 in Figures 1 and 2.

The apparatus is also provided with a safety valve 125 positioned at the top of the housing 1, adjacent the gas outlet 9. This safety valve, which is shown in Figures 2 and 3, is provided as 20 a vent for any explosion that might inadvertently occur in the catalyzing chamber.

In the operation of my improved gas generating apparatus, fuel oil is supplied to the fuel bowl in the manner hereinbefore described and the 25 apparatus started by applying power to the shaft 46. In an installation where the gas generator is employed in connection with an automobile engine, power for the shaft 46 is preferably taken from some positively rotating element of the automobile motor and the apparatus is started by using the usual automobile starter for rotating the motor crank shaft and thus transmitting power to the shaft 46 of the generator. In such 30 an installation, the overflow plunger shaft 91 of the ignition fuel supply device is preferably connected by suitable levers or other means to the automobile starter so that as the starter is operated, the shaft 91 is pulled downwardly to cause the gasoline or other ignition fluid to overflow 35 from the float box 86 into the ignition tube 85. Simultaneously, an electric circuit is made through the contacts 94 and 95 whereby the 40 spark plug 84 is caused to spark so as to ignite the fluid in the ignition tube 85 and the burning of this fluid will ignite the fuel oil that is carried 45 on the periphery of the drum 5 by the wicking 7.

Once combustion has started in the combustion chamber 2 of the generator, the production 50 of gas is quite rapid, which gas is immediately sucked out of the generator through the outlet 9 and into the cylinders of the automobile motor by the action of the motor pistons. The suction on the combustion chamber of the generator 55 produced by the intake suction of the driven motor provides a pressure differential between the air chamber 14 and the atmosphere so that air is taken into the generator through the airport 60 17 at the bottom of the generator housing. The amount of air drawn into the generator is controlled by adjustment of the shutter or slide 118 which controls the size of the openings 16 into the combustion chamber.

At the same time, water having been fed into 65 the vaporizing chamber by the feeder 103 upon the starting of the apparatus, steam is rapidly produced in the vaporizing passageway 26 and such steam together with the air drawn into the air chamber 14 are introduced into the combustion chamber through the adjustable ports 16 and 29 where they promote proper combustion of the fuel oil therein to produce the gas.

In the preferred operation of the herein-described gas generator a fixed gas is produced, 70 which gas is particularly rich in methane and

may be used as fuel in either a hot or cold condition. Also after proper scrubbing the gas may be stored in containers for future use. This gas is produced in the herein-described device, by vaporizing a liquid hydrocarbon and partially burning the vapor in a dampening or smothering atmosphere of superheated steam to develop the heat necessary to support a series of endothermic reactions, starting at a relatively high temperature, within a mixture of the unburned hydrocarbon vapor, the products of combustion and the superheated steam, and in the presence of a suitable catalyst; the constituents of the mixture reacting to produce methane, carbon monoxide, hydrogen, and a small amount of carbon dioxide. 15

A typical analysis of the gas so produced is as follows:

	Percent
CH ₄	17.0
CO	12.6 20
H	9.2
O	0.4
Heavy hydrocarbons	6.8
CO ₂	7.3
N	46.7 25

Reduced to its simplest form, the new process or method in producing methane gas is the equivalent of burning a paraffin wax candle in an atmosphere of superheated steam with just enough air allowed to come into the flame to keep up the heat of the reactions necessary to produce gas; the preferred condition being to cut the air supply far below that which is normally needed to support combustion and to conduct this insufficient air to the center of the flame so as to produce heat with such intensity at this central point that all hydrocarbons and carbon molecules are heated to the temperature of the superheated steam atmosphere in which the candle is burning. 30 The superheated steam atmosphere is preferably held at a temperature above 1800° F. and below 2500° F. 40

At the wick of the herein-described gas generator the combustion is incomplete but sufficient 45 heat is produced by a set of exothermic reactions to not only generate and superheat the water vapor to a point that will allow the separation of the hydrogen from the oxygen but also to raise the whole gas stream to a degree that will allow 50 the completion of the reactions between the elements of the steam and those of the gaseous oil vapors by raising them to a superheated state; thus bringing about conditions that will cause the elements to recombine to form methane. 55

Substantially all of the heat generated within the device is passed along in the gas stream and is utilized in the presence of the catalysts in a series of endothermic reactions which are heat absorbing. This accounts for the fact that when 60 the device is normally operating at temperatures as high as 2500° F. inside; the outer walls do not heat even to redness and the heat loss due to radiation is comparatively low.

The factor or condition set up in my improved 65 process of gas production that serves to keep a balance between the exothermic reactions and the endothermic reactions by which the methane gas is produced is the rapid transfer of the gases and vapors out of the oxidizing or burning zone 70 into the hydrogenizing zone where the heat is needed and absorbed in the formation of the new components. It is for this reason that the gases leave the generator at a reduced temperature that is found to be less than one-third that pro- 75

duced at the zone of combustion. The reactions between the gases formed by partial combustion of the liquid hydrocarbon and the superheated water vapor take place at the ignition temperatures of the different component gases formed in the combustion zone.

In my improved process, all gases are brought to the desired temperature of 1800° F. to 2400° F. by partial combustion which is carried only to the extent necessary to produce sufficient heat for that purpose and before they can complete the burning reaction they are introduced into a new environment under new conditions that do not support combustion; but which environment does permit recombination through entirely different reactions than would normally take place, and results in the formation of different end products having greater heating and power value.

These reactions, which are endothermic and take place in the presence of the catalysts are very rapid and happen as explosions. Thus the two stages of reaction, that is the exothermic and endothermic, take place in a fraction of a second. These reactions are not the mere cracking up of heavier hydrocarbon vapors to lighter hydrocarbon vapors but are chemical reactions in which methane, carbon monoxide, hydrogen and a small amount of carbon dioxide and oxygen are present as a gas mixture.

In my improved process, the desired products are formed in the presence of catalysts which function to stabilize and fix the newly formed methane laden gas before it passes out of the reacting zone so that it has no tendency to recombine with an oil vapor or scrubber, nor have any tendency to condense into light oils. Thus the gas mixture produced by my process will remain as a fixed gas while in storage.

A gas that is fixed has many advantages over gasoline vapor for use in internal combustion engines and one of the principal advantages is that at all temperatures the gas is ready for mixture with fresh incoming air and the colder the incoming air, the more of the gas is available for instant sparking; while with gasoline vapors the gasoline condenses or refuses to be picked up by the cold air and thus causes difficulty in starting in cold weather.

Although but one specific embodiment of this invention has been herein shown and described, it will be understood that details of the method and construction illustrated may be modified or omitted without departing from the spirit of my invention as defined by the following claims:

55 I claim:

1. A gas generator comprising a housing arranged to provide a fuel bowl in its lower portion and a combustion space above said fuel bowl, a horizontally disposed rotatable drum positioned within said combustion space and arranged to extend into fuel held in said fuel bowl, means to rotate said drum, means to ignite fuel carried on said drum, a catalyzing chamber within said housing communicating with said combustion space, catalyzing means in said catalyzing chamber, a tortuous passageway within a wall of said housing adjacent said catalyzing chamber and said combustion space, means to introduce water into said passageway for vaporization therein, means communicating with said passageway and arranged to distribute the water vapors therefrom along one side of said drum, and means to introduce air into said combustion chamber in predetermined quantities and at 75 said one side of said drum.

2. A gas generator comprising a housing arranged to provide a fuel bowl and a combustion space communicating with said fuel bowl, a catalyzing chamber communicating with said combustion space, means to produce combustion of fuel from said fuel bowl in said combustion space, a tortuous passageway in a wall of said housing adjacent said combustion space, means arranged to introduce predetermined quantities of water automatically and intermittently into 10 said passageway for vaporization therein, and means communicating with said passageway to introduce the water vapors into said combustion space substantially at the center of the combustion therein.

3. A gas generator comprising a housing arranged to provide a fuel bowl and a combustion chamber, a rotatable drum disposed horizontally in said combustion chamber and arranged to extend into said fuel bowl, means to rotate said 20 drum, means to ignite fuel carried on the surface of said drum, a tortuous passageway in a wall of said housing and adjacent said combustion chamber, a feeder arranged to supply predetermined quantities of water intermittently 25 into said passageway, means actuated by said means to rotate said drum arranged to control the operation of said feeder according to the speed of rotation of said drum, and means to introduce vapors from said passageway into said 30 combustion chamber.

4. A gas generator comprising a housing arranged to provide a combustion chamber having a fuel bowl in its lower portion, a rotatable drum in said combustion chamber arranged to extend 35 into said fuel bowl, said drum being adapted to carry fuel from said fuel bowl into said combustion chamber, means to rotate said drum, means to ignite fuel carried on said drum, a passage in a wall of said housing extending substantially parallel with the axis of said drum and having a plurality of spaced ports communicating with said combustion chamber adjacent said drum on the side thereof normally emerging from said fuel bowl, means communicating with 45 said passage for providing water vapors thereto for introduction into said combustion chamber, an air passage adjacent and parallel with the first passage and having a row of spaced ports communicating with said combustion chamber, 50 and means to supply air to said air passage.

5. A gas generator comprising a housing arranged to provide a combustion chamber and a catalyzing chamber in communication with each other, means to produce partial combustion of a hydro-carbon fuel in said combustion chamber, means to introduce air and water vapors into said combustion chamber, an outlet from said catalyzing chamber for gases, a catalyst disposed in said catalyzing chamber between said combustion chamber and said outlet, said catalyst comprising a plurality of parallel shafts each carrying a plurality of spaced catalyzing plates fixed transversely of the shaft axis, the plates on one shaft being positioned opposite the spaces between the plates on an adjacent shaft and overlapping the plates on said adjacent shaft, and means to rotate said shafts.

6. In a device of the class described, a catalyst comprising a plurality of parallel rotatable shafts 70 each carrying a plurality of spaced catalyzing discs mounted thereon to rotate therewith and disposed transversely of the shaft axis, said shafts being disposed relative to each other so that the discs on one shaft are positioned oppo-

site the spaces between the discs on an adjacent shaft and in marginal overlapping relationship therewith, and means to rotate said shafts.

7. A gas generator comprising a housing arranged to provide a combustion chamber having a fuel bowl in its lower portion, a rotatable drum in said combustion chamber arranged to extend into said fuel bowl, said drum being adapted to carry fuel from said fuel bowl into said combustion chamber, means to rotate said drum, means to ignite fuel carried on said drum, a passage in a wall of said housing extending sub-

stantially parallel with the axis of said drum and having a plurality of spaced ports communicating with said combustion chamber adjacent said drum and on the side thereof normally emerging from said fuel bowl, means communicating with said passage for providing water vapors thereto for introduction into said combustion chamber, and means to introduce air into said combustion chamber adjacent said spaced ports. 10

VINCENT D. McDONNELL.
